COAL COLORING METHOD

George F. Campbell, Chicago, Ill., assignor to
 Old Ben Coal Corporation, Chicago, Ill., a corporation of Delaware

Application March 13, 1940, Serial No. 323,817

1 Claim. (Cl. 44—6)

This invention pertains to the method and apparatus for identifying coal, and is particularly directed to the application of color or other distinguishing means to coal.

In the past it has been difficult for purchasers of coal to ascertain upon inspection the source of a given lot of coal, and it is an object of my invention to provide means for applying a distinctive color, such as green, to coal so that a buyer may know the mine or mines from which it comes.

Another object is to provide means for feeding coal to dividing or separating means so that a small proportion of the coal from a given lot is separated out for the subsequent step of identifying the smaller amount.

A further object of my invention is to provide conveying means for the coal intermittently disposed along the route of travel of the coal from the hopper to its final destination.

Still another object is to provide means for dividing out the coal that is being conveyed so that upon reaching the spraying means, distinct coloring of each piece of coal is insured.

A still further object is to provide means for heating the coal painted to expedite the drying.

Another and still further object is to provide blower means to additionally expedite the drying of the painted coal.

An additional object is to provide means for conveying the dried painted coal to a place of storage.

Another additional object is to provide means for controlling the feeding of the unpainted coals.

A further additional object is to provide feeding means for the painted coal from its storage so that a definite proportion of painted and unpainted coals is had.

A still further object is to provide means for distribution of the mingled coals to the transporting means.

With these and various other objects in view, the invention will consist of certain novel features of construction and operation as will be more fully described and particularly pointed out in the specification, drawing, and claim appended hereto.

In the drawing, the reference numeral 10 represents the hopper having a dividing gate 12 50

which permits the regulation by delivering any desired portion of coal into the storage receptacle 14, and the balance on to the screen or separating means 16. The smaller pieces of coal will be deposited into the storage receptacle 14 while the large pieces of coal will fall upon the conveyor 18.

Means for adjusting the angle of the flow of the coal from the conveyor 18 is provided at 20. Dividing means 22 is positioned so that the coals will be evenly distributed around the paint sprayers 24. The painted coals will then fall upon the conveyor 26 which has heating means 28 positioned adjacent thereto. In addition to this paint-drying means, a blower 30, positioned near the conveyor to insure the drying of the coal, is provided. A chute or incline 32 is positioned so that the dried or semi-dried painted coals will fall upon another drying conveyor 34, 20 which carries them to the storage 36.

Feeding means 38 is provided to deposit the unpainted coals upon the mixing and loading screen 40. Painted coal feeding means 42 is positioned adjacent the feeding means 38 so that the required proportion of painted coals and unpainted coals is obtained. Mixing vanes 44 are positioned at the end of the feeding means 40 for further intermingling the coals before delivery into the transporting means 46.

An alternative, when treating coals of a more uniform size, would present the following modification. The dividing gate 12 would remove the desired portion of the coal which would pass through a chute instead of the separating means 16, to the conveyor 18, or the adjustable chute 20, and continue on in the same manner as outlined above until they are mixed with the coal from the storage 14.

What I claim and desire to secure by Letters 40 Patent is:

The method of identifying coal consisting of screening a fraction of over-sized lumps from the bulk, uniformly coloring said lumps by spraying color material thereon, drying the color material on the lumps by heating and blowing, and redistributing the lumps with the bulk in controlled proportion as required at the point of distribution to identify the coal.

GEORGE F. CAMPBELL.
